(57) **CLAIM**

The ornamental design for a chair, as shown and described.

DESCRIPTION

FIG. 1 is a front elevational view of a chair showing our new design;

FIG. 2 is a rear elevational view thereof;

FIG. 3 is a top plan view thereof;

FIG. 4 is a bottom plan view thereof;

FIG. 5 a right side elevational view thereof, the left side being a mirror image thereof;

FIG. 6 is a perspective view thereof;

FIG. 7 is a front elevational view of a second embodiment of a chair showing our new design;

FIG. 8 is a rear elevational view thereof;

FIG. 9 is a top plan view thereof;

FIG. 10 is a bottom plan view thereof;

FIG. 11 a right side elevational view thereof, the left side being a mirror image thereof;

FIG. 12 is a perspective view thereof;

FIG. 13 is a front elevational view of a third embodiment of a chair showing our new design;

FIG. 14 is a rear elevational view thereof;

FIG. 15 is a top plan view thereof;

FIG. 16 is a bottom plan view thereof;

FIG. 17 a right side elevational view thereof, the left side being a mirror image thereof;

FIG. 18 is a perspective view thereof;

FIG. 19 is a front elevational view of a fourth embodiment of a chair showing our new design;

FIG. 20 is a rear elevational view thereof;

FIG. 21 is a top plan view thereof;

FIG. 22 is a bottom plan view thereof;

FIG. 23 a right side elevational view thereof, the left side being a mirror image thereof; and,

FIG. 24 is a perspective view thereof.
